UNITED STATES PATENT OFFICE.

ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

TWISTER STOP-MOTION.

941,463.

Specification of Letters Patent. Patented Nov. 30, 1909.

Application filed June 21, 1909. Serial No. 503,264.

To all whom it may concern:

Be it known that I, ALONZO E. RHOADES, a citizen of the United States, and resident of Hopedale, county of Worcester, State of Massachusetts, have invented an Improvement in Twister Stop-Motions, of which the following description, in connection with the accompanying drawing, is a specification, like characters on the drawing representing like parts.

This invention has for its object the production of means for stopping automatically the feed of a plurality of threads or ends passing through the top and bottom rolls of a twisting machine upon breakage of one of the threads before or after leaving the rolls.

My invention is particularly adapted for use in twisters wherein two threads pass together to the rolls to be twisted together, and I have provided automatically acting means to move laterally and off the end of the top roll the plurality of threads passing thereto when one of the threads breaks after leaving the rolls, where breakage usually occurs, or before reaching the top roll.

The various novel features of my invention will be fully described in the subjoined specification and particularly pointed out in the following claims.

Figure 1 is a transverse section of a sufficient portion of a twister to be understood, taken on the line 1-1, Fig. 2, with one embodiment of my invention applied thereto; Fig. 2 is a top plan view of a portion of the mechanism shown in Fig. 1, with the stop-motion for one set of threads operative and for another set in normal, inoperative position; Fig. 3 is a detail in front elevation of one of the deflectors.

The bottom roll *a*, Fig. 1, the top rolls *b* resting upon and driven by the bottom roll and having their journals *b'* loosely held in guides *c*; the traverse-bar *d* having guides *d'* for the set of threads or ends passing to each top roll *b*, and the pig-tails *d''*, Fig. 1, through which the sets of threads pass after leaving the rolls, may be and are all of well-known construction and operate in usual manner.

A horizontal bar 1 extends across the pedestals A back of the rolls between them and the guides *d'*, and behind each top roll *b* said bar has fixedly attached to it a stand 2

provided with rearwardly extended ears 3, 55 and between each pair of ears is pivoted at 4 the hub of an arm 5 upturned at its front end and laterally widened to form a deflector 6 having a cam edge 7, best shown in Fig. 3.

The rear end of arm 5 has an attached leg 8 inclined downward and forward below the bar 1, and terminating in a guide-eye 9, Fig. 1, through which the threads of a set pass as they travel from the rolls to a pig-tail *d''*.

The combined strength of the twisted threads passing from the rolls is sufficient, in connection with the long leverage afforded by the leg 8, to normally maintain the 70 arm 5 and deflector 6 in elevated, full line position, Fig. 1, and as shown at the right, Fig. 2, so that the set of threads passing to the top roll travel below and out of contact with the cam edge 7 of the deflector.

When a thread or end of a set breaks, however, and such breakage usually occurs below the rolls, the tension on the leg 8 is insufficient to maintain it in full line position, the weight of the arm 5 and the 80 deflector then acting to move the deflector, arm and leg into dotted line position, Fig. 1, and as shown at the left Fig. 2. This movement of the deflector causes its cam edge 7 to engage the threads passing to the top 85 roll *b*, the convex shape of the cam edge acting to push the threads laterally toward the end of and off the top roll, thereby stopping the feed of that set of threads.

A slight projection 10 on the underside of the arm 5 drops onto the top of the stand 2 and limits the downward movement of the deflector.

Should a thread of a set break before reaching the rolls the operation just described will be effected, for the diminished strength of the thread passing through the guide-eye 9 will be insufficient to maintain the deflector in its inoperative position.

When the thread is moved off the end of the top roll the feed of such thread of course stops instantly, for it is only by the passage of the thread between the top and bottom rolls that it is nipped and drawn forward.

The construction is simple, there is nothing to get out of order or to become entangled with broken ends, and the operation is prompt and efficient.

Having fully described my invention, what I claim as new and desire to secure by Letters Patent is:—

1. In a twister stop-motion, top and bottom rolls, a guide for a plurality of threads passing thereto, a deflector between said guide and the rolls and movable in parallelism with the normal thread path, and a connected leg provided with a guide-eye 10 through which the threads pass after leaving the rolls, intact threads acting through the leg to maintain the deflector inoperative, release of the leg by breakage of a thread permitting movement of the deflector in the direction of travel of and to engage the threads passing to the top roll and move them axially thereof and off of said roll.
2. In a twister stop-motion, top and bottom rolls, a guide for a plurality of threads 20 passing thereto, a swinging deflector having a cam edge, a connected leg engaged by the threads as they pass from the rolls and maintaining the deflector inoperative, and a fulcrum for said deflector, parallel to the axes of the rolls, breakage of a thread acting through the leg to permit descent of the deflector, the cam edge thereof engaging the threads passing to the top roll and moving them laterally off the end thereof to 25 stop the feed.
3. In a twister stop-motion, top and bottom rolls, a guide for a plurality of threads passing thereto, a deflector pivoted behind the rolls to swing parallel to the normal 30 thread path and having a cam edge, and means acted upon by intact threads as they

leave the rolls to maintain said deflector inoperative, breakage of a thread acting through said means to release the deflector, the cam edge thereof engaging the threads 40 as they pass to the top roll and moving them laterally off the end thereof.

4. In a twister stop-motion, top and bottom rolls, a deflector having a convex side edge and pivotally mounted back of the 45 rolls, and a leg connected with a deflector and engaged by the thread after leaving the rolls, to maintain the convex edge of the deflector normally above the path of the thread passing to the top roll, release of 50 the leg by breakage of a thread permitting the deflector to move its convex edge into and across the path of the thread passing to the top roll, to thereby move such thread laterally off the roll to stop the feed. 55

5. In a twister stop-motion, top and bottom rolls, a gravity actuated deflector movable in parallelism with the normal path of the thread and adapted to engage and move laterally off the end of the top roll a thread 60 passing thereto, and means acted upon by the thread when intact after leaving the rolls to maintain the deflector normally out of engagement with the thread passing to the top roll. 65

In testimony whereof, I have signed my name to this specification, in the presence of two subscribing witnesses.

ALONZO E. RHOADES.
